UNITED STATES PATENT OFFICE.

ERNEST TAYLOR ATWELL, OF WAUKOMIS, OKLAHOMA TERRITORY.

BROOM-HANDLE.

No: 815,058.

Specification of Letters Patent.

Patented March 18, 1906.

Application filed May 6, 1905. Serial No. 257,730.

To all whom it may concern:

Be it known that I, ERNEST TAYLOR ATWELL, a citizen of the United States of America, residing at Waukomis, in the county of Garfield and Territory of Oklahoma, have invented new and useful Improvements in Broom-Handles, of which the following is a specification.

This invention relates to a detachable handle for brooms and other implements, the object of the invention being to provide a handle and means for detachably securing the same to the head of a broom or other implement, whereby when the broom-head or implement is worn out the handle may be quickly and conveniently detached therefrom and attached to another broom-head or implement, the construction thus being adapted to permit the handle to be repeatedly used.

A further object of the invention is to provide a fastening connection whereby the handle may be firmly united to the socket fixed to the broom-head or implement and yet conveniently disconnected at any time.

The preferred embodiment of the invention is illustrated in the accompanying drawings, in which—

Figure 1 is a perspective view showing the application of the invention to a broom. Figs. 2 and 3 are sectional views through the socket looking in opposite directions toward the shank of the broom-handle secured therein. Fig. 4 is a vertical longitudinal section taken on a line through the center of the shank of the handle, and Fig. 5 is a detail view of the locking key and wedge.

Referring now more particularly to the drawings, the numeral 1 designates the head or brush portion of a broom, which is provided with the usual handle-receiving socket 2, and 3 designates the broom-handle.

The bore 4 of the socket is formed with an upper cylindrical portion 4' and a lower flaring portion 5, and at its upper end the cylindrical portion 4' is outwardly curved or flared to form a seat 6. The handle 3 is provided at one end with a reduced tang or shank 7, provided at its point of junction with the body of the handle with a rounded contact portion or shoulder 8, adapted to engage the seat 6 when the shank or tang 7 is inserted in the socket and limit the downward movement of the handle, and at the same time form a firm abutment to prevent

independent play of the parts. Below the shoulder 8 the tang or shank 7 is split or divided by a longitudinal slot 9. Secured to the handle immediately above the shoulder 8 is a plate or strip 10, which strengthens the handle at that point and forms a guide and stop for a locking-key 11. The key fits and slides longitudinally in a guide-groove 12, formed in the tang and communicating at its upper end with an enlarged groove or mortise 13, formed in the base portion of the body of the handle and extending a short distance above the upper end of the plate or strip 10, which latter bridges or extends across said mortise. The key 11 is provided with an offset upper end 14, which bears against the inner face of the plate or strip 10 at the front of the mortise 13, and is provided with a terminal finger-piece 15, projecting outwardly beyond said mortise and adapted to abut against the upper end of the plate 10, whereby the downward movement of the key is limited.

The lower end of the key is formed upon one side with a wedge 16, having its thin or edge end upwardly directed and projecting normally into the lower end of the slot 9 in the tang or shank 7. By this construction it will be seen that when the finger-piece 15 is moved upwardly in the mortise 13 to the dotted-line position shown in Fig. 4 the key will be moved longitudinally upward and the wedge 16 forced into the slot 9, thereby spreading the sides of the tang 7 and expanding the same into contact with the lower flared portion 5 of the bore 4 of the socket 2, thus securely fastening the handle to the socket. Upon forcing the finger-piece 15 down into the mortise again the wedge 16 will be restored to its normal position, (shown in Fig. 2,) thus permitting the sections of the shank to move together by their natural elasticity, whereupon the handle may be easily disconnected from the socket. If desired, the flared portion of the wall of the socket 2 may be coated with a roughening or adhesive material, such as rosin, to prevent any possibility of the slipping of the shank when expanded therein. By the construction of parts described a detachable handle is provided which may be conveniently applied and removed and repeatedly used in connection with a number of broom-heads, thus obviating the necessity of providing a handle for each broom-head.

Having thus described the invention, what is claimed as new is—

1. In a detachable handle, the combination of a socket, a handle having a split shank to enter the socket, and a sliding operating element carrying a wedge having an upwardly-directed point adapted to be drawn between the portions of the shank to spread the same apart and into frictional engagement with the walls of the socket.

2. In a detachable handle, the combination of a socket, a handle provided with a split shank and having a longitudinal groove extending above the shank and terminating in a mortise, a stop-piece inclosing the handle

above the shank and below the upper portion of the mortise, and a key sliding in said groove and mortise and provided at its lower end with a shank-expanding wedge and at its upper end with a finger-piece projecting laterally from the mortise and adapted to be limited in its downward movement by the stop-piece.

In testimony whereof I affix my signature in presence of two witnesses.

ERNEST TAYLOR ATWELL.
